SPARK PLUG

George R. Smith, Flint, Mich., assignor to C. V. S. Manufacturing Company, Flint, Mich., a corporation of Michigan

Application December 12, 1936, Serial No. 115,612

3 Claims. (Cl. 123—169)

My invention relates generally to spark plugs, and particularly to a spark plug of that type which is known in the art as a combination, two-piece type, and an important object of my invention is to provide a spark plug incorporating the features of the so-called one-piece spark plug with the advantageous features of a two-piece type spark plug, thereby eliminating disadvantageous features of these types of spark plugs while retaining and enhancing the advantageous features thereof, affecting performance and manufacture.

Another important object of my invention is to provide a combination spark plug of the character indicated which permits the efficient use of a shorter insulator without impairing the required insulation against high tension spark jumping between the shell and the top of the center electrode, often referred to as "flash-over", so as to provide for increased efficiency in the operation of the spark plug, while enhancing the resistance thereof to breakage from mechanical shock.

Other important objects of my invention will be apparent from a reading of the following description taken in connection with the drawing, wherein for purposes of illustration I have shown a preferred embodiment of my invention.

In the drawing:—

30 Figure 1 is a sectional elevational view of an embodiment of my invention.

Figure 2 is an enlarged side elevational view of a metallic bushing in accordance with the present invention and showing the same with the neck and wrench receiving portion which is removed in the manufacture and assembling of the spark plug.

Referring in detail to the drawing, the numeral 5 generally designates the spark plug shell which includes the usual grounded electrode or sparking point 6, the numeral 7 generally designates the porcelain or other suitable material insulator in which the central electrode 8 is mounted and sealed, which central electrode has the sparking point 9 in close proximity to the sparking point 6, and the binding post 10 at its upper end and exposed above the top of the insulator. The numeral 11 generally designates the all-metal bushing of the present invention which holds the insulator or core 7 in place in the shell 5 as indicated in Figure 1 of the drawing.

As shown in Figure 2, the metal bushing 11 is, before the finishing and assembling operations, composed of a cylindrical body portion 55 which is exteriorly threaded as indicated by the

5 numeral 12 for a comparatively short distance below the outstanding annulus 13 which is flat on its underside as indicated by the numeral 14 and curved or rounded on its upper side as indicated by the numeral 15. A portion of reduced diameter 16 rises above the annulus 13 and on its top is the laterally extending wrench receiving flange 17 which is flat on its top as indicated by the numeral 18. The lower end of the bore of the bushing is rounded as indicated 10 by the numeral 19 for engagement with the exterior of the insulator or core 7 as indicated in Figure 1 of the drawing.

In the conventional one-piece spark plug construction there are several advantageous features 15 which are not present in the conventional two-piece type of spark plug. For instance, it requires a longer and hence more expensive and easily broken porcelain insulator to produce the desired dielectric conditions, so that the resultant spark plug is not only subject to breakage from mechanical shock, such as a slipping wrench or careless handling or dropping of the spark plug, especially in engines in which the operating compression is high in the cylinders, and 20 an unusually long path between the top exposed end of the central electrode within the core, and the top of the metal part of the shell or bushing is required to prevent shorting and "flashing-over". The lengthening of this path of the high 30 tension current can be easily accomplished in a one-piece type of spark plug, and at the same time the insulator may be reduced in length or height in view of the fact that considerable metal required for the hex bushing in other 35 forms of spark plugs is eliminated. Further, the cost of providing and handling the hex bushing is eliminated in the one-piece type of spark plug.

A disadvantageous feature of the one-piece spark plug device lies in the fact that in sealing the metallic shell or casing, it is difficult to accomplish a satisfactory job without injuring or cracking the porcelain insulator, because of the great strain necessarily placed on this part. Further it is difficult to control this pressure so as to definitely provide for different heat ranges. After a one-piece spark plug has been assembled and sealed, there can be no salvage of the insulator or shell if either or both be found defective after final testing, either in the 45 respect of pressure leakage around the sealing of the shell or electrical leakage around the central electrode at the top of the porcelain or pressure leakage at this point.

The conventional two-piece type of spark plug 55

has advantages and disadvantages. The method whereby the metallic shell is sealed around the insulator, by engaging or fastening the threaded hex bushing to cause it to exert sufficient pressure against the top and bottom gaskets, is required to prevent loss of compression. Control of this operation is easier than the method utilized in sealing a one-piece spark plug as pointed out above, and is less likely to injure or crack the porcelain body. Furthermore, in the two-piece type of spark plug if the same be found defective in any manner after final assembly and test, the same can be disassembled and valuable parts thereof salvaged. It has been recommended that a two-piece spark plug be taken apart and cleaned after it has been in service for some time, and that it be then reassembled and restored to service. But this procedure has objectionable features which eliminates its desirability generally.

Further, the diameter and length of the insulator in the two-piece type of spark plug is restricted to a considerable extent because of the conventional type of hex bushing used, and this restriction results in a frangible insulator which is not able to resist any considerable mechanical shock. The vertical extension of the hex bushing above the metallic shell even after it has been tightened down, makes necessary an insulator which extends to a greater vertical height than otherwise would be required, to provide the necessary distance between the top of the central electrode and the body of the spark plug, to prevent the jumping of the high tension current therebetween.

In the present invention a combination type is evolved which incorporates the advantageous features of the one-piece type of spark plug which produce efficient performance and a stronger porcelain insulator, as regards mechanical shock. While in the present invention the total cost of the hex bushing is not eliminated, the cost is less than that for the one piece type of sealing, since as already pointed out, valuable parts of the one-piece spark plug must be scrapped when found defective by a test by the manufacturer.

The advantageous character of the spark plug of the present invention is made possible in main by the removal of the upper part of the hex nut or bushing 11 as shown in the drawing, thereby enabling the utilization of a shorter and hence stronger insulator which nevertheless provides the necessary insulating distance between the top of the body of the spark plug and the upper end of the central electrode.

The reduced portion 16 and the wrench receiving flange 17 are cut off by any suitable operation after the spark plug has been completely assembled and tested. If on final test or inspection the spark plug is found defective, it can still be disassembled and the valuable parts thereof salvaged, and this operation of disassembly or removal of the bushing may be accomplished in a manner to avoid injuring the spark plug in any way, and no further testing is required.

A comparison of the invention with the conventional types of two-piece spark plugs will clearly show that a much longer electrical path is made possible between the metallic shell and the top of the central electrode where a comparably long insulator is used. It follows from this that a shorter insulator 7 can be used while still providing a required distance to eliminate flash-over or shorting between the shell and the top of the center electrode. This shortening of the insulator strengthens it naturally against mechanical shock.

Another advantage of the present invention is that it cannot be disassembled or tampered with after leaving the factory. Further, the invention is of great importance because of the smaller type of spark plugs being manufactured in increasing quantities, such as the 14 mm., and its value is relatively greater in the still smaller sizes, such as the 10 mm. and the 12 mm.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A method of making a spark plug having an increased dielectric distance between the sealing bushing and the upper end of the central electrode exposed at the top of the core, said method comprising removing the wrench receiving portion from the top of the bushing and reducing the top of the bushing so as to be substantially flush with the top of the shell of the spark plug.

2. A spark plug comprising a tubular shell having an interior shoulder located intermediate the upper and lower ends thereof, a tubular bushing threaded into the upper end of said shell and having a lateral projection engaged with the upper end of the shell and substantially flush therewith, an insulator surrounded by said shell and said bushing, said insulator having a laterally projecting annular part resting on said interior shoulder with the lower end of said bushing engaging the top of said annular part.

3. A spark plug comprising a tubular shell having an interior shoulder, an insulator surrounded by said shell and having an annular projection resting directly upon said interior shoulder whereby the upper part of the insulator extends above the upper end of the shell to a conventional height, a tubular bushing surrounding said insulator and threaded into the upper end of said shell, said bushing engaging its lower end directly with the top of said annular projection, and an annulus on the upper end of said bushing engaging an upper part of said shell, the top of said annulus being rounded to merge substantially flush with the top of said shell.
